UNITED STATES PATENT OFFICE.

FRANCIS HYDE, OF TORONTO, ONTARIO, CANADA.

SELF-CLOSING TAP.

SPECIFICATION forming part of Letters Patent No. 297,691, dated April 29, 1884.

Application filed March 12, 1883. (No model.)

To all whom it may concern:

Be it known that I, FRANCIS HYDE, of the city of Toronto, in the county of York, in the Province of Ontario, Canada, have invented 5 a new and useful Self-Closing Tap; and I do hereby declare that the following is a full, clear, and exact description of the same.

My invention relates to that class of taps which are used by plumbers in the fitting up 10 of bath-rooms, water-closets, wash-basins, and for general purposes where common taps are used.

My invention has for its object the prevention 15 of the waste of water which takes place from the common taps being left open, and, besides causing a loss of water, the apartments in which the taps are placed are frequently flooded from the same cause, and considerable damage done thereby.

20 In the accompanying drawings, Figure 1 is an elevation, and Fig. 2 a sectional elevation, of my self-closing tap. Fig. 3 is a sectional elevation of the valve and stem, and also the valve-seat, with metallic washer above the 25 same. Fig. 4 is a cross-section of the valve-stem, through that portion which slides up and down through the valve-seat, which is also shown in this figure. Fig. 5 is a plan view of the base of my tap.

30 Similar letters of reference indicate similar parts in all the views and in this specification.

A represents my self-closing tap; a, the button on top of valve-stem; b, the stem, the lower portion of which is three-sided, making 35 provision for the water to pass through between the stem and the seat, as shown in Fig. 4; c, a gland of the stuffing-box in the upper end of the tap; d, a spiral spring located between the button and the gland, for the purpose of assisting the closing of the valve; e, the stuffing-box, which is filled with soft greased packing; f, the body of the tap; g, the delivery-nozzle; h, the valve closing up-

wardly on a flat seat, but tapering downwardly for the easier opening thereof, which is easier 45 pressed down than with a flat surface; h', the valve-seat, of prepared rubber or other suitable material; h'', a metallic flanged washer located above the seat, which is pressed down on the same, and makes a solid body for the 50 face of the valve to act upon; i, the base of the tap, which is secured, in the present case, on a basin-table; J, a threaded stem, which passes through the table, and on which a nut is placed and secures the tap thereon.

55 My tap is intended to be placed in others besides a vertical position. The valve will operate as well as in a vertical position.

The operation of my self-closing tap, as shown in the drawings, is as follows: The tap 60 is opened by pressing down the button a, which also presses down the valve h, leaving an opening between the valve h and the seat h'. The stem b being three-sided at this part, as hereinbefore described, the 65 water rushes through at these three points, and is discharged from the delivery-nozzle. On removal of the finger from the button a, the pressure of the water on the back of the valve, with a very slight assistance from the 70 spiral spring d, will immediately close the valve of the tap, and it will remain closed till again required.

Having thus described my invention, I claim—

75 In a faucet, the valve-body A and threaded stem J, combined with the valve-stem b, triangular in cross-section and carrying the upwardly-seating valve h, valve-seat h', and metallic flanged washer h'', the whole arranged 80 substantially as set forth.

FRANCIS HYDE.
